UNITED STATES PATENT OFFICE.

SAMUEL STEINECKE, OF BROOKLYN, ASSIGNOR TO CHRISTIAN A. SCHMIDT, OF NEW YORK, N. Y.

DESIGN FOR A CURTAIN-BAND.

SPECIFICATION forming part of Design No. 13,711, dated March 6, 1883.

Application filed January 29, 1883. Term of patent 14 years.

To all whom it may concern:

Be it known that I, SAMUEL STEINECKE, of Brooklyn, of the county of Kings and State of New York, have invented a new and Improved 5 Design for Curtain-Bands, of which the following is a full, clear, and exact description.

Reference is to be had to the accompanying drawing, which is a plan view of a curtain-band illustrating my design.

10 The leading feature of my design consists in the chenille threads crossing each other in pairs between the edges of the band, and the thread wound around the said edges.

15 The body of the curtain-band is formed of chenille threads A, connected with the edges of the band and crossing each other in pairs,

intermediate between the said edges. The edges of the band have a thread, B, wound around them, giving a finish to the said edges.

Having thus described my invention, I claim 20 as new and desire to secure by Letters Patent—

The design for a curtain-band herein shown and described, the same consisting of chenille threads A, crossing each other in pairs, intermediate between the edges of the band, and 25 a thread, B, wound around the edges of the band.

SAMUEL STEINECKE.
